UNITED STATES PATENT OFFICE.

JULIUS MANN, OF NEW YORK, N. Y.

LOCK.

Application filed July 29, 1921. Serial No. 488,439.

To all whom it may concern:

Be it known that I, JULIUS MANN, a citizen of Poland (having taken out first United States citizenship papers), and a resident of the city of New York, borough of Manhattan, in the county and State of New York, have invented a new and Improved Lock, of which the following is a full, clear, and exact description.

10 This invention relates to locks and has for an object to provide an improved construction which may act in the ordinary capacity of door locks or may act in conjunction with a link as a safety catch for a door 15 when ajar.

Another object of the invention is to provide a locking structure with a locking bolt and a link pivotally mounted on the keeper of the lock arranged to co-act with 20 the bolt to present a link safety device for holding the door partially open and at the same time locked.

Another object of the invention is to provide a lock with a locking bolt and mechanism for actuating the same which in addition, acts to lock the bolt against actuation when set to certain positions.

An additional object of the invention is to provide a lock which may be set against 30 operation by an authorized person or an unauthorized person from the outside or from the inside.

In the accompanying drawings—

Figure 1 is a vertical longitudinal sectional view through a lock embodying the invention as the same appears when in use, the section being taken on line 1—1 of Figure 2.

Figure 2 is a horizontal sectional view 40 through Figure 1 on line 2—2.

Figure 3 is a view similar to Figure 1 but showing the parts in a different position.

Figure 4 is a fragmentary sectional view 45 similar to part of Figure 3 but showing the locking mechanism in a different position.

Figure 5 is a view similar to Figure 4 but looking at the locking mechanism from 50 the opposite direction.

Figure 6 is a view similar to Figure 5 but showing the parts in a different position with the bolt slightly advanced toward a projected position.

55 Figure 7 is a sectional view through Figure 1 approximately on line 7—7.

Figure 8 is an inverted view of a locking bar embodying certain features of the invention.

Referring to the accompanying drawings 60 by numeral, 1 indicates a door of any desired kind and 2 a door jamb. Connected with the door 1 is a lock 3 and connected with the jamb 2 is a keeper 4 of a special construction and provided with a link 5 65 which acts in a general way the same as a night chain now in common use. The keeper 4 is enlarged at its outer end so as to present locking abutments 6 and 7, said abutments being spaced apart in order to 70 present a groove 8. These abutments are also undercut to provide passage-ways 9 for the bolt 10. This bolt is provided with a spring receiving stem 11 and laterally extending shoulders 12, a neck 13 and a locking head 14. The locking head 14 is wider than neck 13 and is provided with rounded shoulders 15, which under some circumstances, strikes the rounded surfaces 16 of members 6 and 7. Each of these members 80 is provided with a lug 17 which carries a pivot 18 and which is provided with two flat surfaces 19 and 20. These surfaces are adapted to be engaged at different times by the spring 21 so as to resiliently hold the 85 link 5 in the position shown in Figure 2 or in the dotted position shown in said figure. The link 5 is provided with a pair of ears 22 which straddle the lug 17 and which are pivotally mounted thereon by the pins 90 18. The link 5 is also provided with an enlarged opening 23 through which the head 14 of bolt 10 may project, said opening merging into a restricted notch 24 which readily accommodates the neck 13 of bolt 95 10 but through which the head 14 cannot pass.

When the parts are in the position shown in Figure 2, the bolt 10 may be projected outwardly and the head 14 forced through opening 23. The link 5 may then be swung over manually to the dotted position shown in Figure 2 and after which the door 1 opens as indicated in dotted lines in Figure 1. It will be noted that when this takes place the door is locked against opening beyond the length of the link 5 and that the door must be closed before the bolt can be retracted. Also, by reason of the undercut portions of members 6 and 7 for providing the grooves 110 8, the bolt 10 must be projected in order to open the door and if projected will extend

2
into the opening 23 but will not interlock with the link 5 unless said link is manually moved over to the dotted position shown in Figure 2. In case the door should be open 5 and the bolt 10 retracted, the door may be readily closed by using some force, as the curved surfaces 15 of the bolt head 14 will strike the curved surfaces 16 of members 6 and 7 and will be automatically projected 10 against the action of the spring 25 and then retracted into the position shown in Figure 1 which is the locking position.

It will be evident that the bolt 10 and associated parts forming the lock may be 15 used in connection with the keeper 4 either with or without the link 5 though this particular form of bolt is especially adapted for use in connection with this link.

In constructing the lock, the bolt 10 is carried by a casing 26 which is provided with a 20 division wall or partition 27 having an aperture 28 formed therein as well as a notch 29, said aperture accommodating the shank 11 while the notch 29 accommodates the shoulders 12. It will, therefore, be seen that the 25 bolt 10 is guided by the shank 11 operating in the aperture 28 and the neck 13 operating in the aperture 30 formed in the end of casing 27. The shank 11 of the bolt 10 is 30 rigidly secured to an end member or abutment 31, which end member or abutment is provided with a flange 32 and a shoulder 33 preferably provided with a contact surface 34 arranged at a slight angle to the remaining 35 part of the shoulder in order to engage properly the end of the locking bar 35 hereinafter fully described. The abutment 31 reciprocates with the bolt 10 and when moved to the position shown in Figure 3 40 compresses spring 25. In order to move the abutment 31 together with the bolt 10 against the action of spring 25, two actuators are provided, namely, actuators 36 and 37, actuator 36 being connected with 45 the hand operated knob 38 arranged interiorly of the door 1 while the actuator 37 is connected with the mechanism of an ordinary tumbler lock 39. The tumbler lock 39 is operated by a key in the usual manner 50 and when rotated rotates the actuator 37 in either direction as desired for locking or unlocking the lock 3. However, these actuators are so formed as to be set not only to lock the bolt 10 in a locking position but to 55 lock the bolt against actuation by the opposite actuator.

When the parts are in the position shown in Figure 1, either actuator may operate the bolt while the position of the parts in Figure 4 shown with the bolt may be actuated only by the actuator 36. When the parts are in the position shown in Figure 5, the bolt can be actuated only by the actuator 37. In this way the lock may be set to prevent 60 anyone from the exterior unlocking the 65

same even with a proper key. Also, the lock may be set to prevent anyone from the interior unlocking the lock by actuating the knob 38. When the parts are in the position shown in Figure 1 and it is desired to lock the bolt 10 against movement, the actuator 36 is rotated in the direction of arrow 40 until the notch 41 straddles the flange or web 32 as illustrated in Figure 4. The abutment 31 is cut away on the lower surface 75 except near the end carrying the web 32, which end is provided with an extension 42. In this way, ample space is assured for the free passage of the actuator 36 beneath the abutment and around to the position shown in Figure 4. Preferably, both ends of the actuator 36 are bent upwardly from the body of the actuator so that the part carrying the notch 41 will readily strike web 32 when moved to the position shown in Figure 4 and the actuating end 36' will strike the projection 42 when the actuator is operating to project the bolt as shown in Figure 3.

It is, of course, understood that the actuator 36 is connected with the knob 38, said connection being in any desirable manner, as for instance, by a suitable short shaft 43, which is rigidly secured to the actuator 36 extends through the wall of casing 26 and is rigidly secured to the knob 38. When the parts are in the position shown in Figure 1 and it is desired to actuate or project the bolt 10, a key is inserted into the locking mechanism 39 and rotated in the direction indicated by the arrow 44 in Figure 3. When this has been done, the bent up section 45 of the actuator 36 will engage the abutment 31 adjacent the shoulder 33 and will move the parts to their projected position.

In Figure 6, the actuator 37 is shown as beginning to project the bolt. It will be noted that the bar 35 is resting against pin 46 and is held in that position by a spring 47 acting against the flat surfaces 48. When the bar 35 is resting against the pin 49, 110 spring 47 acts against the surface 50 for preventing accidental shifting of the bar. The knob 38 as shown in Figure 2 is connected to the inner wall 51 of the casing 36 and when in the position shown in Figure 6 is 115 out of the way of the shoulder 33 so that the bolt may freely reciprocate. In case it should be desirable to lock the bolt against operation from the inside or by the knob 38, the actuator 37 is moved in the opposite direction to the arrow 44 (Fig. 3) until the same shifts the bar 35 to the position shown in Figure 5. When in this position, the end of the bar 35 is in the path of movement of the shoulder 33 and, consequently, the bolt 10 cannot be moved against the action of spring 25. When the parts are in this position, knob 38 cannot shift the bolt which can be done only by actuator 37 which is moved by the locking mechanism 39 and the 120 125 130 135

actuator 37 can only actuate the bolt after it has first shifted the bar 35 back to the position shown in Figure 4. It will be noted that the bar 35 is pivotally mounted on the wall 51 and freely swings except for the action of spring 47. This bar is provided with an undercut 52 which permits the extension 53 of the actuator 37 to freely pass when moving from the position shown in Figure 10 1 to that shown in Figure 6. In moving in this direction, the extension 53 acts to throw the bar 35 back to its inoperative position as shown in Figures 4 and 6.

What I claim is:—

15 1. A lock comprising a keeper, a bolt, means for actuating said bolt from the interior, means for actuating said bolt from the exterior, and a spring pressed locking bar pivoted adjacent the bolt actuated by the 20 exterior operating means preventing operation of said bolt from the interior after it has been locked from the exterior.

25 2. A lock comprising a keeper, a locking bolt, said bolt being provided with an abutment having a projection, a manually actuated thumb member, and an actuator connected with said thumb member, said actuator being provided with a notch and a pressure portion, said pressure portion acting to actuate said bolt, said notch receiving said projection of said abutment and thereby locking the bolt against movement, permitting the bolt being unlocked only by the thumb operating actuator.

35 3. A lock comprising a spring pressed bolt, said spring acting to retract the bolt, a pair of actuators, means including a hand operated knob for operating one of the actuators, and means including a key operated locking mechanism for operating the other actuator, the first mentioned actuator being formed with means capable of locking the bolt against actuation by the other actuator, and a locking bar actuated by the second 40 45 mentioned actuator for preventing actuation of the bolt by the first mentioned actuator.

4. A lock of the character described comprising a spring pressed bolt, said spring

acting to retract the bolt, an abutment carried by the bolt provided with a shoulder 50 and with a projecting web, a locking bar adapted to engage the shoulder for locking the bolt against actuation, a knob operated actuator for actuating the bolt, said hand operated actuator being formed with means interlocking with said web for locking the bolt in its retracted position, a second actuator, and key actuated means for moving said second mentioned actuator, said second mentioned actuator being provided with projections which act to actuate the bolt, shift said bar to a position in front of said shoulder and shift the bar away from said shoulder according to the movement of the actuator. 55 60 65

5. A lock of the character described, comprising a keeper, a locking mechanism associated with said keeper and including a bolt adapted to be projected into the keeper to lock the two together, a pair of locking elements for locking said bolt against movement, one of said elements being operable from the exterior, the other from the interior, said elements being adapted to lock said bolt independently of each other, and 70 75 said bolt once locked can only be opened by operating the lock elements locking the bolt to thereby prevent the opening of the lock from the side opposite from which it was locked. 80

6. A lock of the character described, comprising a keeper, a link pivotally mounted on said keeper and provided adjacent the pivoted end with an enlarged opening, a bolt having a shank and a head, and means for shifting said bolt into said enlarged opening, said means comprising an actuator operable from the interior and an actuator operable from the exterior independently of each other, said bolt once shifted forwardly by one of said actuators can only be returned to its normal position by operating the same actuator to thereby prevent the lock being opened from the side opposite from which it was locked. 85 90

JULIUS MANN.
